UNITED STATES PATENT OFFICE.

JOHN C. HAWKER, OF PANA, ILLINOIS.

IMPROVEMENT IN END-GATES FOR VEHICLES.

Specification forming part of Letters Patent No. **151,023**, dated May 19, 1874; application filed February 7, 1874.

To all whom it may concern:

Be it known that I, JOHN C. HAWKER, of Pana, in the county of Christian and State of Illinois, have invented a new and useful Improvement in End-Board Fastenings, of which the following is a specification:

The object of this invention is to furnish a durable and convenient fastening for the end-boards of wagons, and convenient means for adjusting it in unloading the wagon; and it consists in the construction and arrangement of parts hereinafter described.

In the accompanying drawing, Figure 1 is a side view. Fig. 2 is a back end view of the wagon, showing the end-board.

Similar letters of reference indicate corresponding parts.

A A are the side-boards, and B is the bottom board, of the wagon-box. C is the end-board. D D represent plates on the ends of the side-boards A A, which plates are riveted or made fast to the side-boards. The lower ends of these plates hook under and support the bottom board, as seen at E E. F are hook-recesses in the edges of these plates, and the ends of the side-boards are cut out to correspond. These hook-recesses F receive the ends of the fastening-bars G. These bars are screwed or riveted to the end-board, as seen in Fig. 2. The parts which enter the recesses F project and have each a flat bolt-head, H, which prevents the side of the wagon-body from spreading. From the two upper heads H button-pins I project, to which are attached the ends of the chains J. K K are hooks firmly attached to the side-boards A.

In unloading the wagon it is sometimes necessary to deliver the contents back from the wagon-body. For this purpose I adjust the end-board, as seen in Fig. 1, on a level with the bottom of the wagon-body, and support it in that position by the chains J, attached to the hooks K, and by the two lower fastening-bars, which are dropped into the two lower hook-recesses L L.

Fig. 2 represents the end-board as closed. The fastening-bars G drop into the recesses F, which brings the top of the end-board to a level with the top of the side-boards.

For ordinary purposes the end-board is sufficiently fastened by the hooks; but for greater security bolts M M may be applied, which engage with recesses in the side-boards, as indicated in Fig. 2.

Having thus described my invention, I claim as new and desire to secure by Letters Patent—

1. An end-board, C, provided with fastening-bars G, having flange-heads H, in combination with side plates D, having hook-recesses F F, as shown and described.

2. An end-board, C, provided with bars G, supplementary bolts M M, button-pins I I, and chains J, in combination with side plates D, hooks L L, hooks E E, and chain-hooks K, all constructed as and for the purpose specified.

JOHN C. HAWKER.
